(57) **CLAIM**

The ornamental design for a cockpit center console, as shown and described.

DESCRIPTION

FIG. 1 is a perspective view showing our new design of a cockpit center console;

FIG. 2 is a first side view of the cockpit center console of FIG. 1;

FIG. 3 is a view of a second side opposite the first side of the cockpit center console of FIG. 1;

FIG. 4 is a top view of the cockpit center console of FIG. 1;

FIG. 5 is a front view of the cockpit center console of FIG. 1; and,

FIG. 6 is a perspective view from within an aircraft cockpit of the cockpit center console of FIG. 1.

In FIGS. 1-6, the broken lines illustrate the environment of the design and portions of the cockpit center console that form no part of the claimed design.
